EDWARD J. TOMLINSON, OF NEWARK, NEW JERSEY, ASSIGNOR TO SPLITDORF ELECTRICAL COMPANY, OF NEWARK, NEW JERSEY.

DESIGN FOR A PHONOGRAPH-METER.

56,544.

Specification for Design.

Patented Nov. 2, 1920.

Application filed December 6, 1919. Serial No. 343,083. Term of patent 7 years.

To all whom it may concern:

Be it known that I, EDWARD J. TOMLINSON, a citizen of the United States, residing at Newark, in the county of Essex, State of New Jersey, have invented a certain new, original, and ornamental Design for Phonograph-Meters, of which the following is a description, reference being had to the accompanying drawing, forming a part thereof.

The single figure of the drawing is a per-

spective view of a phonograph meter in which the speed of rotation of the phonograph sound record body is visually registered by the meter.

I claim:

The ornamental design for a phonograph meter, as shown.

In testimony whereof, I affix my signature.

EDWARD J. TOMLINSON.
